(57) **CLAIM**

The ornamental design for a therapeutic device for localized headache and pain treatment, as shown and described.

DESCRIPTION

FIG. 1 is a perspective view of a therapeutic device for localized headache and pain treatment, showing my new design;

FIG. 2 is a front view thereof;

FIG. 3 is a left view thereof;

FIG. 4 is a right view thereof;

FIG. 5 is a back view thereof;

FIG. 6 is a top view thereof;

FIG. 7 is a bottom view thereof; and,

FIG. 8 is a side view thereof in a configuration use.

The broken lines in the drawings are for the purpose of illustrating portions of the therapeutic device for localized headache and pain treatment, which form no part of the claimed design. The additional broken lines shown in FIG. 8 are for the purpose of illustrating environmental structure, which form no part of the claimed design.
